UNITED STATES PATENT OFFICE.

NICHOLAS DEDRICK, OF MANITOWOC, WISCONSIN.

NAIL-SETTING MACHINE.

1,178,441.

Specification of Letters Patent. Patented Apr. 4, 1916.

Application filed April 25, 1914. Serial No. 834,419.

To all whom it may concern:

Be it known that I, NICHOLAS DEDRICK, of Manitowoc, Wisconsin, have invented a Nail-Setting Machine, of which the following is a specification.

This invention is a device for a special purpose which can be briefly described as follows: In the manufacture of purses, the material of the purse consisting of leather or the like has its edge riveted to a metal frame which forms the closure member of the purse. The metal frame consists of a border of sheet metal through which and the edge of the leather rivets are placed; a second strip of sheet metal to hold the upset ends of the rivets from tearing through the leather is placed on the inside, and the rivet upset over this strip. The rivets consist originally of small round-headed pointed nails the ends of which, after they are set in place, are cut off by nippers and the nails then upset. Heretofore this operation has been performed entirely by hand.

The object of the present machine is to provide means for setting the nails in place ready for cutting off and riveting. Nails are ordinarily automatically fed from a pile one by one to a holder, picked up by said holder and held pointed end up upon an anvil while the material, consisting of the frame, leather and riveting-strip are pressed down over the point. I also provide means for automatically causing the nail to be thrust through the material.

The apparatus is illustrated in the accompanying drawings, wherein—

Figure 1 is a front-view of a complete machine, the bench or table upon which it stands being shown in section; Fig. 2 is a side-view thereof, some of the parts at the rear of the view being omitted to avoid confusion; Fig. 3 is a longitudinal section on the plane 3, showing the hammer depressed to effect the thrusting through of the nail, some of the parts at the rear of the view being omitted to avoid confusion; Fig. 4 is a plan-view of the complete machine; Fig. 5 is a plan-section thereof on the plane 5, showing the nail-tongs or holder in position to receive a nail; Fig. 6 is a plan-section on the plane 6, showing the nail-holder in the position in which it releases the nail after the operation and starts on a new cycle of operations; Fig. 7 is a sectional elevation on the plane 7; Fig. 8 is a fragmentary sectional elevation on the plane 8; Fig. 9 is a sectional

elevation on the plane 9; Fig. 10 is a transverse section through the feed-hopper on the plane 10, and on a larger scale than the preceding drawings; Fig. 11 is a plan-view of the hopper, the cover being removed, and with a part of the margin thereof broken away; and Fig. 12 is a plan-section of the locking-device for the nail-holder on the plane 12 and on a larger scale than the other figures.

In these drawings each reference numeral or letter designates the same part in every figure.

The apparatus is mounted on a plate-shaped base A provided with screw-holes a^1 through which may be inserted screws a^2 (see Fig. 7) whereby it may be secured to a bench or table B. The bench or table is herein shown in section and is provided with a hole b^1 bored in it, through which extends the lower end of a tubular standard C, which is mounted and supported upon the plate A. As shown in Fig. 3, the tubular standard C is provided with a shoulder c^1 on the underside of the plate A, and with a thread c^2 above it, which is engaged by a nut c^3 , securely clamping the standard in place. The standard C is made tubular to receive the shaft D, which is also made tubular for purposes hereinafter described. The shaft D extends both above and below the respective ends of the tubular standard C, and at its upper end there is mounted the horizontal swinging-carrier E, which is perforated by a hole through which passes the threaded stud d^1 on the upper end of the tubular shaft D, and the carrier E is secured in place thereon by a nut d^2 on the end of the threaded stud, and of course suitably keyed so that it cannot turn on the shaft. A member F is intercalated between the nut d^1 and the carrier E, as shown, for purposes hereinafter explained. In its position of rest, shown in Figs. 1, 2 and 3, the swing-arm E comes to rest upon the upper end of the tubular standard C and the latter forms an abutment therefor. Standard C is rabbed around its upper edge to receive an annular cushion c^4 of fiber or like material. The carrier E performs the function of conveying the nails one by one from the nail-holding magazine G on the left of the machine and the auxiliary devices whereby the tacks are taken one by one from said magazine and delivered to the carrier (or swing-arm) E, and by it brought to the anvil H at

the front of the machine; and the nail I is held on the anvil by the carrier (see Fig. 3) during the operation of forcing the point of the nail I through the leather J of the purse.

5 For the purpose named the carrier E is provided on its free end with a fixed nail-holding blade or finger e^1 and a movable nail-holding blade or finger k^1 , the finger e^1 being secured by screws e^2 to the end of the 10 member E, and the finger k^1 being secured by screws k^2 to the member K which is pivoted upon a pivot-screw k^3 so that said fingers e^1 and k^1 act together in the manner of a pair of shears or tongs to hold the nails I.

15 The member K has an arm k^4 which extends rearwardly and is connected in a yielding manner to the body of the carrier E by means of a small spring k^5 attached to posts e^3 and k^6 on the members E and K respectively. The left-hand or movable finger k^1 also has in its front end a small notch k^7 , leaving between it and the finger k^1 a recess slightly smaller than the shank of the nail, whereby the nail is held with sufficient firmness for the purpose in view through the action of the coiled spring k^5 . That is to say, this is the case when the carrier E is presented to the nail-placing devices which deliver a nail to the fingers and during the 20 carrying-movement when the carrier is returning to its position on the anvil, that is to say, from the position shown in Fig. 5 to the position shown in Fig. 4; but, in the latter position, the spring k^5 alone is not relied 25 on to hold the nail I in place during the operation of forcing the nail through the leather, but the member K is also held in a position to hold the finger k^1 firmly against the nail by a spring-bolt m^1 , which is mounted upon a standard or post M at the right of the carrier. The spring-bolt m^1 is pressed forward by a coiled-spring m^2 (see Fig. 12) which is compressed within the bore in which the bolt m^1 is mounted and 30 abuts against the bolt m^1 at one end and against the headless-screw m^3 at the other. A cross-bar m^4 , traversing the bolt m^1 and a pair of slots m^5 on opposite sides of the bolt, limits the movement of the latter. The end 35 of the bolt m^1 is chamfered or cut-off obliquely from the top down for the purpose of enabling the arm k^4 to push the bolt back when it descends as the carrier E resumes its position upon the anvil; for it is to be 40 understood that the carrier E and shaft D do not merely turn horizontally upon the axis of the shaft, but they also have a concomitant vertical movement, which is effected in the following manner: In the 45 lower part of the tubular standard C, which is below the plate A, are cut two oppositely disposed cam-slots c^5 , said slots having their lower ends vertical, that is to say, parallel to the axis of the shaft, their intermediate portions helical, and their upper ends again

vertical, as clearly shown in the several figures of the drawing. With these cam-slots coöperate a pair of rollers d^3 , which are mounted upon pivot-screws d^4 , which are screwed into the opposite sides of the shaft 70 D. Now, it will be seen that the weight of the apparatus causes the shaft D, carrier E and attached parts to assume normally the position shown in Figs. 1, 2, 3 and 7, in which the carrier rests upon the anvil H, 75 the shaft D is at the lower end of its movement, and the rollers d^3 are in the vertical lower end-portions of the cam-slots c^5 . Now an upward pressure upon the lower end of the shaft D, effected as hereinafter described, will cause said shaft and the carrier E first to rise vertically, until the rollers d^3 strike the helical intermediate portions of the slots c^5 ; and thereupon the carrier and shaft will be caused to continue 80 the rising movement with a rotation added thereto, and this will be continued until the carrier E reaches the position shown in Fig. 5, that is to say, reaches the limit of its rotational movement; the rollers d^3 now strike 85 the vertical upper end-portions of the slots c^5 and the carrier E will be given a vertical upward movement, bringing it into the dotted-line position shown in Fig. 7. Contrariwise, when the carrier E returns to its 90 original position it will first descend, then swing around to a position immediately over the anvil, and finally descend to a position of rest as hereinbefore described; and, in this movement, the end of the arm k^4 , striking the beveled end of the bolt m^1 , will press back the latter so that the bolt will exercise its force upon the end of the arm k^4 to hold the nails in place between the fingers e^1 and k^1 as the carrier comes to a position in which 95 the head of the nail I rests on the anvil.

The nail-magazine G, which is illustrated in detail in Figs. 8 to 11 inclusive, comprises an upright tubular post g^1 which is mounted on the plate A, as for example by having a plug g^2 fixed in its lower end bored and threaded to engage with a screw g^3 or any other suitable arrangement, and carries at its upper end a hopper g^4 which receives the nails. Said hopper is for convenience provided with a movable cover g^5 , which is pivoted upon an upright post g^6 at one side thereof, and to hold it in place a coiled compression-spring g^7 is disposed upon the post g^6 above the cover g^5 and is held in firm 110 abutment with the latter by means of a set-collar g^8 clamped by a screw g^9 . The cover g^5 may have a handle g^{10} and a pair of ears or clips g^{11} on opposite sides which engage 115 the sides of the hopper g^4 to keep the cover in place. Within the tubular post g^1 is mounted a sliding member g^{12} , said member being preferably flattened and the post g^1 flattened correspondingly so as to form a 120 close guard therefor. In its upper end the 125

sliding member g^{12} is longitudinally slit parallel to its broader side by a narrow deep recess g^{13} , the width of which is just sufficient to admit the shanks of the nails but not their heads. It will be seen from Fig. 9 that the upper end of the member g^{12} is cut off obliquely sloping toward the left, and in its lowered position said sloping upper end lies below the bottom of the hopper so that, 5 when in this position, if there are any nails in the hopper, one or more of them will fall into the slot g^{13} and will slide to the lower end thereof as shown in Fig. 9, being supported by their heads, and the shanks of the 10 nails depending in the slot g^{13} . In this position the ends of the slot are closed by the sides of the post g^{12} , and continuations of said sides are formed by the upright bars g^{14} and g^{15} , whose opposing edges are caved as shown, so as to form effectively 15 guides for the member g^{12} when it is raised. On the higher or right-hand side of the sliding member g^{12} the post g^{15} is carried up to the top of the hopper, but on the left-hand 20 side the post g^{14} is connected with a sloping chute g^{16} , which has a slot g^{17} forming a continuation of the slot g^{13} , and the upper edge of said chute forms a continuation of the upper edge of the member g^{12} when in 25 its raised position, so that any nails which are caught in said slot g^{13} when the member g^{12} is in its lowered position are, when the member g^{12} is raised, released and slide down the chute g^{16} until they reach the end 30 thereof as shown in Fig. 9, said chute passing through the wall of the hopper g^4 and the end thereof lying outside the hopper. At this point, the further movement of the 35 nails is barred by a pair of small spring-fingers g^{18} , secured to the outer side of the chute and hopper g^4 in such manner that they project over the ends of the chute (see Fig. 11). In order to prevent the nails which are caught in the slot g^{13} from being 40 thrown out of it over the top as the member g^{12} is suddenly checked in its rising movement, another pair of spring-fingers g^{19} , secured to the opposite sides of the post g^{15} (see Fig. 11), are so disposed as to project 45 over and close to the upper end of the member g^{12} when in its raised position, thereby checking any such jumping movement of the 50 nails. The reciprocating movement of the member g^{12} is effected by means of an 55 arm N , the end of which projects through a hole g^{20} in the lower end of the member g^{12} , slots g^{21} being also formed in the opposite sides of the hollow post g^1 to enable the arm N to move up and down freely. Said arm 60 N (see Figs. 5, 6 and 7) is pivoted upon a pin n^1 in a post n^2 mounted on the plate A , and its rising movement is effectuated by means of the member F already referred to, which is mounted upon the stud d^1 of the 65 shaft D immediately over the carrier E , said

member F having, as clearly shown in Figs. 1 and 7, two arms f^1 and f^2 , the former of which is bent up and the latter down. The downwardly bent arm f^2 has a laterally projecting toe f^3 , which is chamfered or beveled 70 on its upper face as clearly shown in Fig. 6, and is so placed that when the carrier E turns upon its axis, the arm f^2 turning with it causes the toe f^3 to engage under the member N , and in the final vertically upward 75 movement of the carrier this engagement causes the arm N to be raised and thus to raise the reciprocating member g^{12} , so that at each cycle of operations one or more nails will be carried from the bottom of the hopper 80 and delivered into the chute g^{16} , and thence slide to the lower end thereof, where they are ready to be delivered to the devices which will now be described for placing the 85 nails between the fingers of the nail-holder or tongs.

As will be seen from Figs. 7, 8 and 9, the lower end of the chute g^{16} projects outside the hopper and into a position directly under a vertically reciprocating detaching pin 90 O , mounted to reciprocate in the hollow post g^6 . The vertical movement of this pin is limited by a transverse pin o^1 , which is set in the pin O and the ends of which project into slots g^{22} in the sides of the post g^6 95 where the latter projects below the wall of the hopper g^4 . The lower end of this post g^6 is also widened and bored to receive the upper end p^1 of the nail-reversing member P , said member being secured in place by a set-screw g^{23} . The member P is hollowed out 100 interiorly and is set opposite the end of the chute g^{16} , and, as will be seen from Fig. 9, the hollow interior chamber p^3 of said member extends above the head of the adjacent nail which is suspended at the lower end of the chute, but there is a crossbar p^4 which lies opposite the lower end of the nail in position to cause the latter to be overturned in falling, as shown by the dotted-line positions thereof when the head-end of the nail is pushed laterally toward the left. This latter movement is effected by the lower 105 wedge-shaped end of the vertically reciprocating pin O , when the latter is depressed, 110 the edge of said wedge-shaped end coming between the lowermost two nails in the chute and thus causing the lowermost nail to push aside the spring-fingers g^{18} and to be forcibly thrown over into the chamber p^3 . Normally the pin O is supported in a yielding manner by the coiled compression-spring o^2 115 surrounding its upper end and resting upon the collar g^8 or upper end of the post g^6 and upon a cross-pin o^3 . The depression-movement of the pin O is effected by the upper end of the arm f^1 of the member F , which, as plainly seen in Fig. 1, projects in this position over the upper end of the pin O , and it carries a set-screw f^4 and lock-nut f^5 by 120 125 130

which the amount of depression of the member O can be nicely regulated. It will be understood, of course, that the actual depression takes place on the return-movement 5 of the carrier as it comes back to its position over the anvil and descends vertically thereupon.

Directly under the member P there is mounted a hollow post Q, which is secured 10 to the base-plate A by a screw q^1 threaded into the lower end thereof, or by any other suitable means. This post Q contains a reciprocating plunger q^2 , which has an enlarged head q^3 on its lower end, this end 15 being slotted transversely to receive the end of an arm R which reciprocates in lateral slots q^4 in the post Q, and is pivoted upon a pivot-pin r^1 on the upper end of a post r^2 mounted on the base A. The upper end of 20 the post Q is interiorly threaded to receive a tubular head q^5 , the bore of said head being just sufficient to admit a nail I thereinto as shown, and as the upper end of the plunger q^2 projects into said bore, it will be understood, of course, that it has the same diameter. Within the post Q, surrounding the plunger q^2 , and having an abutment at one 25 end upon the head q^5 and at the other upon the head q^3 , is a coiled compression-spring q^6 , which acts to assist the force of gravity in returning the plunger q^2 to its lower position as shown in Figs. 7 and 9.

The nail I does not fall from the reversing-box P directly into the tubular bore 30 of the head q^5 , but into a funnel s^1 , which is mounted on the swing-arm S, pivoted on a pivot-screw s^2 mounted on the upper end of the post s^3 . Said funnel s^1 acts as a guide to carry the nail head-downward into the upper end of the post Q. The arm S has a 35 swinging movement upon the end of the post s^3 through a small angle, and it is kept yieldingly pressed forward by a coiled torsion-spring s^4 (Figs. 1 and 7) having one end engaging in a hole near the base of the arm S and the other end in a supporting-collar s^5 , which is secured to the post s^3 by a set-screw s^6 . The post s^3 is mounted upon the plate A and may be secured thereto by a 40 screw s^7 threaded into its lower end, as shown in Fig. 7. The forward travel of the arm S is limited by an abutment-block s^8 , which strikes against the side of the head q^5 in a position in which the funnel s^2 is in 45 exact registry with the bore of the head q^5 . Thus it will be seen that when the pin O is depressed in the manner aforesaid, the nail I at the bottom of the chute g^{10} will be thrown off, and being tripped by the bar p^3 50 is turned head down and so falls into the funnel s^1 by which it is guided so that it lands in the bore of the head q^5 as shown in Fig. 9. Now, in order that the nail I which has been delivered into the bore of the 55 head q^5 may be delivered between the fingers

e^1 and k^1 when they are brought by the rotational movement of the carrier E into a position in which the notch k^7 is directly over the bore q^5 , the funnel s^1 is set upon the movable arm S so that it can be swung 70 out of the way, and this swinging movement of the arm S is effectuated by devices carried on the carrier E and best illustrated in Figs. 3 and 7, and their action best illustrated by the plan-view, Fig. 5. The pivot-screw k^3 which forms the pivot of the member K is extended downwardly as shown in Fig. 3 to form also the shaft or axis of the roller e^4 , which is secured in place by a nut e^5 engaging the threaded lower end of the member k^3 . This roller e^4 is so disposed as to strike the front side of the arm S when the carrier E swings around and to swing said arm S backwardly, as shown in Fig. 5, until the end thereof comes to abut upon the side of a downwardly projecting piece e^6 secured to one side of the carrier E by a screw e^7 . Such abutment limits the swinging movement of the carrier E as well as of the arm S. Now, as will be seen from Figs. 90 4 and 5, the arm S forms one of a pair of guide-fingers, S, s^9 , both pivoted upon the pivot-screw s^3 and held yieldingly together by the coiled-spring s^{10} which is hooked into the eyes of a pair of posts s^{11} and s^{12} 95 mounted respectively on the members S and s^9 . At a point on the line between these two members S and s^9 which is immediately over and in registry with the bore of the head q^5 when the parts are in the positions 100 shown in Fig. 5, they are notched out to form the conical hole s^{13} , one-half of the hole forming a semi-conical notch in each piece, so that the pointed end of the nail I, and following it the head thereof and the 105 upper end of the plunger q^2 , can be pushed up through the conical-hole s^{13} and in so doing spread the members S and s^9 so as to give passage to the head of the nail and the upper end of the plunger q^2 . The hole 110 s^{13} acts, therefore, as a guide to hold the nail upright while it is passing from the bore q^5 into the notch k^7 between the fingers e^1 and k^1 . On the carrier E opposite the abutment-piece e^6 and secured by the same 115 screw, e^7 , is a downwardly extending member e^8 , having a toe e^9 bent horizontally at right angles to the lower end thereof (see Fig. 7). The toe e^9 is adapted to take under the arm R as the carrier E swings around, 120 and as the latter rises it will also raise the arm R, so that by the time the carrier has reached the limit of its rotational movement the arm R will have raised the plunger q^2 , and the nail I supported thereby, sufficiently 125 so that the end of the nail will be ready to pass into the notch k^7 between the fingers s^1 and k^1 . The final vertical rising movement of the carrier heretofore described, and which now takes place, causes the arm 130

R to be raised sufficiently to bring the nail I into the position I' shown in dotted lines in Fig. 7, where it has been thrust between and is supported by the fingers e^1 , k^1 . On the 5 return-movement a vertical drop first takes place, in which the plunger q^2 will drop below the member S, and the members S and s^9 will come together again so as to close the hole s^{13} . The head of the nail I now 10 being above the member S and over the small end of the hole s^{13} , can no longer pass through the latter so that in striking thereupon it is thrust farther upward between the fingers e^1 and k^1 , until the latter support it 15 directly under the head as they start on their return movement. Of course, if the nail should not have been pressed quite up to the head between the fingers e^1 and k^1 , it will be so pressed when the latter come 20 down upon the anvil H.

The apparatus as thus far described is sufficiently complete in itself to be operated so far as the operation of taking the nail and setting it in position or thrusting it 25 through the leather is concerned. However, in the most improved form of my apparatus, I prefer to provide means whereby the nail can be mechanically thrust through the leather, which is particularly advantageous 30 where the leather is thick, and the point of the nail rather blunt. Such means consist of a hammer the point of which is hollowed to receive the point of the nail, and which therefore strikes only upon the leather or 35 rather upon the perforated metal plate which is placed over the leather, and not upon the nail itself. This construction, best illustrated in Figs. 2 and 3, is as follows: The shaft D is longitudinally bored to receive 40 a rod T, which at its upper end is screwed into a bored and threaded head-piece t^1 as shown, and the shaft D is chamfered out at d^3 to receive a coiled compression-spring t^2 , which rests upon the lower 45 end of the recess d^3 and presses upwardly upon the head-piece t^1 , causing the latter and the rod T to be normally raised to the upper limit of its movement. The member t^1 is transversely slotted at t^3 to receive the 50 shank of the flattened hammer-arm U, which is pivoted at its rear end upon a pin v^1 traversing a slot v^2 on the upper-end of a post V, which is fixed to the rearwardly projecting end of the carrier E. The shank 55 of the hammer-arm U, where it passes through the slot t^3 of member t^1 , has a parallel-sided slot u^1 to receive a roller t^4 , which turns upon a pin t^5 , mounted in the end of the member t^1 and projecting across 60 the slots t^3 and u^1 . This arrangement constitutes effective means whereby, on the depression of the rod T, the hammer-arm U is carried downwardly into the position shown in full lines in Fig. 3. The front or 65 free end of the arm U carries a heavy

weight u^2 , and is turned downwardly as shown at u^3 , and the end thereof longitudinally bored as shown at u^4 , and disposed in such a position that the nail I which is held between the fingers e^1 and k^1 will pass into the bore u^4 when the member U is depressed. As an additional guide for the hammer-arm U, a post W is mounted on the carrier E in front of the member t^1 , and is slotted at w^1 to receive the hammer-arm U and has a cushion at its lower end in the form of a fiber-strip w^2 for an abutment when the hammer-arm U is depressed.

As accessory apparatus, an adjustable guide is provided for the material of the purse, said guide consisting of the curved standard X, which is clamped to the inner face of the anvil H by a thumb-screw x^1 , one edge thereof abutting against the pin x^2 , and its upper end being bent to the rear as shown at x^3 , Fig. 2, and the guide-member x^4 being adjustably secured thereto by screws x^5 , passing through slots x^6 in the end x^3 of the standard, so that the member x^4 has a slight longitudinal adjustment. The front end x^7 of the member x^4 is bent at right-angles transversely to the anvil to form a stop or abutment for the sheet-metal edge-piece j^1 of the purse, as shown in Fig. 3.

The operation of taking a nail from the magazine and setting it in place on the anvil, as above described, being effected by an upward movement of the shaft D, and the operation of hammering the leather down upon the nail by a downward movement of the rod T, both are effected by the same treadle, or other hand or foot-operated device connected to a rod Y in connection with the following arrangement: Upon the lower end of the shaft D is screwed the nut d^4 which acts as an abutment against the lower end of the standard C, to limit the upward movement of the shaft. The lower end of the rod T carries a ball-end t^6 , which forms with the inclosing members y^1 and y^2 a ball-joint, the members y^1 and y^2 being screw-threaded together as shown and the latter being bored and tapped to receive the threaded end of the rod Y. A fiber-washer y^3 acts as a cushion for abutment against the end of the shaft D. When the rod Y is thrust upwardly the movement is transmitted through the washer y^3 to the shaft D and the operations already described by which the nail is manipulated and brought into place are carried out, and when the rod Y is pulled downwardly after the carrier E has come back into place the movement of the shaft D ceases and the rod T is pulled down, causing the hammer-arm U to be depressed and driving the nail I through the leather J. By then releasing the tension upon the rod Y, the spring t^2 will raise the hammer-arm U and rod T and restore the parts to their initial positions.

- There remains to be described the manner in which the nail, having been set in the edge of the purse, is caused to be released by the nail-holding fingers e^1 and k^1 .
- 5 The rearwardly extending end of the arm k^4 of the member K carries a pointed toe k^8 with which coöperates a bolt or latch m^6 , carried on the end of a plate-spring m^7 , which is secured by screws m^8 on the side 10 of the post M. The latch m^6 is so disposed as to be pushed back during the return-movement of the carrier by the toe k^8 , and finally to engage with the latter as shown; but when the carrier begins its next advance-movement, it will retain the toe k^8 for a short distance at the beginning of the movement and thereby cause the fingers e^1 and k^1 to separate, as illustrated in Fig. 6, so as to release the nail, which is now held 15 by the edge of the purse; and the purse having been removed, the fingers will, of course, on the further movement of the carrier, snap together again when the toe k^8 passes off the end of the latch m^6 .
- 20 25 The further operations upon the nail, consisting in cutting off the end thereof and riveting the remaining portion in place, are not performed by this machine and form no part of the object of this invention.
- 30 35 As an additional means of firmly holding the carrier during the hammering operation upon the anvil, the post M is provided with an extension m^9 which passes under the carrier and has a hooked end m^{10} in position to engage the left-hand side of the carrier when it descends, thereby acting as an opposing force to the pressure of the bolt m^1 upon the arm k^4 and preventing any yielding of the latter.
- 40 45 It will, of course, be understood that the foregoing description includes many details which are not of the essence of the invention, or not material or necessary thereto, and that others need not be made in the exact form described, but other equivalent devices may be substituted within the scope of the invention, as will be readily apparent to those skilled in the art.
- Having thus described my invention, 50 what I claim as new and desire to secure by Letters Patent is:
1. In a machine of the class described, the combination of an anvil, a nail-magazine, and a carrier arranged to take a nail from said magazine, deliver it to said anvil and hold it point up thereupon.
  2. In a machine of the class described, the combination of a carrier having nail-holding means, means for moving said carrier cyclically from one position to another, a device adapted to deliver a nail to said nail-holding means in one position of said carrier, and mechanism connected with said carrier and operating said device to deliver

a nail to said nail-holding means when the latter is in position to receive it.

3. In a machine of the class described, the combination of a carrier having nail-holding means, means for moving said carrier cyclically from one position to another, a device adapted to deliver a nail to said nail-holding means in one position of said carrier, a mechanism operating said device and connected with said carrier to deliver a nail to said nail-holding means when the latter is in position to receive it, a nail-magazine, and means for feeding the nails one by one from said magazine to said device.

4. In a machine of the class described, the combination of a carrier having nail-holding means, means for moving said carrier cyclically from one position to another, a device adapted to deliver a nail to said nail-holding means in one position of said carrier, a mechanism operating said device and connected with said carrier to deliver a nail to said nail-holding means when the latter is in position to receive it, a nail-magazine and mechanism operated by said carrier once during each cycle for taking a nail from said magazine and delivering it to said device.

5. In a machine of the class described, the combination of a carrier having nail-holding means adapted to hold a nail and having a given position of rest in which the nail is supported for operation upon it, means in said position adapted to abut against the head of the nail and support it by so abutting, means for giving said carrier a cyclical movement, and a hammer adapted to exert a blow upon the material of the goods through which said nail it to be thrust, so as to thrust it through said goods, said hammer being constructed and arranged to strike the goods on opposite sides of said nail without striking the nail itself.

6. In a machine of the class described, the combination of a movable carrier having a position of rest and having nail-holding means, means arranged to abut upon the head of the nail in said position of rest and support it against thrust upon the point, and a device adapted to depress the goods upon said nail and thrust the latter through them.

7. In a machine of the class described, the combination of a movable carrier having nail-holding means and having a position of rest in which the nail is supported for operation thereupon, a device adapted to depress the goods upon said nail and thrust the latter through them while said nail is in said position, and a device adapted in a different position of said carrier to deliver a nail to said nail-holding means.

8. In a machine of the class described, the

combination of a movable carrier having nail-holding means and having a position of rest in which the nail is supported for operation thereupon, a device adapted to 5 depress the goods upon said nail and thrust the latter through them while said nail is in said position, and a device adapted in a different position of said carrier to deliver a nail to said nail-holding means; said device being mechanically operated by said carrier as it reaches said position to cause it to deliver a nail to said nail-holding means.

9. In a machine of the class described, the 15 combination of a movable carrier having nail-holding means and having a position of rest in which the nail is supported for operation thereupon, a device adapted to depress the goods upon said nail and thrust 20 the latter through them while said nail is in said position, and a device adapted in a different position of said carrier to deliver a nail to said nail-holding means; said device being mechanically operated by said 25 carrier as it reaches said position to cause it to deliver a nail to said nail-holding means, a nail-magazine, and mechanism adapted to deliver the nails one by one from said magazine to said device.

30 10. In a machine of the class described, the combination of a movable carrier having nail-holding means and having a position of rest in which the nail is supported for operation thereupon, a device adapted to de- 35 press the goods upon said nail and thrust the latter through them while said nail is in said position, and a device adapted in a different position of said carrier to deliver a nail to said nail-holding means; said de- 40 vice being mechanically operated by said carrier as it reaches said position to cause it to deliver a nail to said nail-holding means, a nail-magazine, and mechanism adapted to deliver the nails one by one from 45 said magazine to said device, said mechanism being operated by the movement of said carrier.

11. In a machine of the class described, the 50 combination of a movable carrier having a position of rest and having a nail-holding means adapted when in said position of rest to support a nail in position for thrusting the point thereof through the material of the goods, a device operated by the move- 55 ment of said carrier to deliver a nail there- to in another position thereof, means for driving the point of the nail through the material of the goods and a movable element adapted on motion in one direction 60 from its neutral position, to cause said carrier to move to said second position, and to have a nail delivered to the nail-holding means and on its return movement to bring said carrier back with the nail to said po-

sition of rest, and by a motion in the other 65 direction from the neutral position to cause said nail to be driven through the material of the goods.

12. In a machine of the class described, the combination of a movable carrier having 70 a position of rest and having a nail-holding means adapted when in said position of rest to support a nail in position for thrusting the point thereof through the material of the goods, a device operated by the move- 75 ment of said carrier, to deliver a nail there- to in another position thereof, means for driving the point of the nail through the material of the goods, a movable element adapted on motion in one direction from its 80 neutral position, to cause said carrier to move to said second position, and to have a nail delivered to the nail-holding means and on its return movement to bring said carrier back with the nail to said position of rest, 85 and by a motion in the other direction from the neutral position to cause said nail to be driven through the material of the goods, a nail-magazine, and mechanism operated by the movement of said carrier for delivering 90 nails one by one with each cyclical move- ment of the carrier to said device.

13. The combination of a nail-carrier having a cyclical movement and having nail- 95 holding means comprising a recess in which the shank of the nail is held frictionally, a member having a bore adapted to receive a nail and disposed directly in line with said recess in the nail-receiving position of said carrier, and a plunger in said member adapt- 100 ed when the carrier is in said position to push the nail out of said bore and deliver it to said nail-holding means.

14. The combination of a nail-carrier having a cyclical movement and having a nail- 105 holding means comprising a recess in which the shank of the nail is held frictionally, a member having a bore adapted to receive a nail and disposed directly in line with said recess in the nail-receiving position of said carrier, a plunger in said member adapted when the carrier is in said position to push the nail out of said bore and deliver it to said nail-holding means, a sloping nail-chute mounted over said member and adapted to 110 carry a line of nails, means for detaching nails one by one from the lower end of said chute, and means for guiding the nail so detached into said bore.

15. The combination of a nail-carrier having a cyclical movement and having nail- 120 holding means comprising a recess in which the shank of the nail is held frictionally, a member having a bore adapted to receive a nail and disposed directly in line with said recess in the nail-receiving position of said carrier, a plunger in said member adapted when the carrier is in said position to push 125

the nail out of said bore and deliver it to said nail-holding means, a sloping nail-chute mounted over said member and adapted to carry a line of nails, means for detaching 5 nails one by one from the lower end of said chute, means for reversing the position of the nail as it falls, and means for guiding the nail so detached into said bore.

16. The combination of a nail-carrier having a cyclical movement and having nail-holding means comprising a recess in which the shank of the nail is held frictionally, a member having a bore adapted to receive a nail and disposed directly in line with said recess in the nail-receiving position of said carrier, a plunger in said member adapted when the carrier is in said position to push the nail out of said bore and deliver it to said nail-holding means, a sloping nail-chute 10 mounted over said member and adapted to carry a line of nails, means for detaching nails one by one from the lower end of said chute, means for overturning the nail as it falls, a laterally shiftable funnel in one position registering with said bore so as to guide the falling nails thereinto and in another position adapted to be moved away from the end of said bore, and means operated in connection with the carrier for moving 15 said funnel to said last named position when the nail-holding means is in position to receive a nail from said bore.

17. The combination of a sloping nail-chute adapted to contain a line of nails, 20 means for detaching nails one by one from the lower end thereof, a member having a vertical bore in its upper end adapted to receive a nail, a plunger in said bore below the nail adapted to push it out of said bore when raised, a laterally shiftable member carrying a funnel which in one position of said laterally shiftable member registers with said bore and is adapted to receive the nail detached from the chute and guide it 25 into said bore and in another position of said lateral member is moved to one side of said bore, said laterally shiftable member having at one side of said funnel and adapted to register in said last named position with said bore, a conical hole, said hole being formed in two elements which are yieldingly held together so as to be spread apart when the nail passes up through them, said conical hole acting as a guide for the nail as it is 30 pushed up by said plunger, a laterally shiftable carrier having nail-carrying means which is in one position of said carrier in line with said bore whereby the nail which is pushed up through said bore by said plunger is delivered to said nail-carrying means and is guided thereinto by said conical hole, means operated by said carrier when in said position to raise said plunger whereby to cause the delivery of a nail to said nail-holding means, and means operated by said carrier when in another position for causing the detachment of a nail from said chute.

18. The combination of a sloping nail-chute adapted to contain a line of nails, means for detaching nails one by one from the lower end thereof, a member having a bore in its upper end adapted to receive a nail, a plunger in said bore below the nail adapted to push it out of said bore, a laterally shiftable member carrying a funnel which in one position of said laterally shiftable member registers with said bore and is adapted to receive the nail detached from the chute and guide it into said bore and in another position of said shiftable member is moved to one side of said bore, said laterally shiftable member having a conical hole at one side of said funnel and adapted to register in said last-named position with said bore, said hole being formed in two elements which are yieldingly held together so as to be spread apart when the nail passes up through them, said conical hole acting as a guide for the nail as its is pushed up by said plunger, a laterally shiftable carrier having nail-carrying means which is in one position of said carrier in line with said bore whereby the nail which is pushed up through said bore by said plunger is delivered to said nail-carrying means and is guided thereinto by said conical hole, means operated by said carrier when in said position to raise said plunger whereby to cause the delivery of a nail to said nail-holding means, and means operated by said carrier when in another position for causing the detachment of a nail from said chute.

19. The combination of a tubular standard, an upright shaft mounted in said standard, a swinging arm mounted on the upper end of said shaft and constituting a carrier, nail-holding means at the free end of said arm, means for imparting to said shaft and arm first a rising movement, then a rotary movement about the axis of the shaft and then again a rising movement, and a nail-delivering device operated by said last-named movement of the carrier to deliver a nail point up to said nail-holding means.

20. The combination of a tubular standard, an upright shaft mounted in said standard, a swinging arm mounted on the upper end of said shaft and constituting a carrier, nail-holding means at the free end of said arm, means for imparting to said shaft and arm first a rising movement, then a rotary movement about the axis of the shaft and then again a rising movement, a nail-delivering device operated by said last-named movement of the carrier to deliver a nail point up to said nail-holding means, a nail-magazine having a nail-chute, means for detaching nails one by one from the lower end of said chute and delivering them successively to said nail-delivering device, and a connection between said last-named means and said arm whereby on its lowering move-

ment into the last-named position, said means are actuated to deliver a nail to said nail-delivering device.

21. The combination of a tubular standard, an upright shaft mounted in said standard, a swinging arm mounted on the upper end of said shaft and constituting a carrier and having an operating position, nail-holding means at the free end of said arm, means for imparting to said shaft and arm first a rising movement, then a rotary movement about the axis of the shaft and then again a rising movement, a nail-delivering device operated by said last-named movement to 15 the carrier to deliver a nail point up to said nail-holding means, a depressible hammer-arm having a hollow point, said hammer-arm being mounted so as when depressed to come down over the nail so that the nail 20 enters the recess in the end thereof, and means for depressing said hammer-arm when the nail is supported in aforesaid operating position.

22. In a machine of the class described, 25 the combination of a swinging carrier-arm having at its free end a nail-holding means which consists of a pair of fingers pivoted together, one of said fingers being stationary on the end of the arm, a member pivoted on 30 said arm on which the other finger is mounted, said member having a rearward extension from the pivot, means for yieldingly holding the two fingers together whereby a nail can be frictionally supported between 35 them, and a locking-device adapted to abut against said rearward extension thereby locking the two fingers firmly together when said arm is in said position.

23. In a machine of the class described, 40 the combination of a swinging carrier-arm having at its free end a nail-holding means which consists of a pair of fingers pivoted together, one of said fingers being stationary on the end of the arm, a member pivoted on 45 said arm on which the other finger is mounted, said member having a rearward extension from the pivot, means for yieldingly holding the two fingers together whereby a nail can be frictionally supported between 50 them, a locking-device adapted to abut against said rearward extension thereby locking the two fingers firmly together when said arm is in said position, and a latch device acting on said rearward extension to 55 cause said fingers to open sufficiently to re-

lease the nail when said arm swings out of said position.

24. In a machine of the class described, the combination of a swinging carrier-arm having at its free end a nail-holding means 60 which consists of a pair of fingers pivoted together, one of said fingers being stationary on the end of the arm, a member pivoted on said arm on which the other finger is mounted, said member having a rearward extension from the pivot, means for yieldingly holding the two fingers together whereby a nail can be frictionally supported between them, means for giving to said arm a turning or swinging movement and subsequently 65 a lowering movement, and a spring-bolt adapted in said lowering movement to be struck and be pushed aside by said rearward extension and thereby come to press firmly against the latter so as to hold said fingers 70 firmly pressed together in said position.

25. In a machine of the class described, the combination of a carrier adapted to assume a given position of rest and to hold 80 a nail point up in position for depressing the material of the work upon the point thereof when in said position of rest, and a nail-magazine at one side of said position of rest of the carrier; said carrier having a movement from its aforesaid position to said 85 magazine and back and being adapted to take a nail from said magazine and hold it for operation in the aforesaid position.

26. In a machine of the class described, the combination of a swinging carrier-arm 90 having at its free end a nail-holding means which consists of a pair of fingers pivoted together, means for yieldingly holding the two fingers together whereby a nail can be frictionally supported between them, said 95 carrier-arm having a position of rest in which the nail is adapted to be operated on, means for giving to said arm a turning or swinging movement from said position of rest, and a device arranged as said carrier-arm returns to its position of rest to clamp said fingers together, whereby the nail is firmly held by them during the operation upon said nail.

In witness whereof, I have hereunto set 105 my hand in the presence of two witnesses.

NICHOLAS DEDRICK.
